UNITED STATES PATENT OFFICE.

CHARLES W. MOORE, OF SOUTH BEND, INDIANA.

STREET OR STATION INDICATOR.

1,222,015.

Specification of Letters Patent. Patented Apr. 10, 1917.

Application filed February 15, 1915. Serial No. 8,435.

To all whom it may concern:

Be it known that I, CHARLES W. MOORE, a citizen of the United States, and residing at South Bend, county of St. Joseph, and

5 State of Indiana, have invented a new and useful Improvement in Street or Station Indicators, of which the following is a specification.

My invention relates to that class of devices which provide means for indicating to passengers in street railway or railroad cars, the next street crossing or station, in such manner as will enable said passengers to give to the conductor of said street rail- 10 way or railroad cars the signal to stop the car when it arrives at the street crossing or station at which they wish to get off.

The object of my invention is to provide means for exhibiting a successive series of 20 street or station names corresponding to the cross streets or stations which are traversed by a street or railroad car, and means for indicating in succession the next street or station intersection.

25 Another object of my device is to provide means for reversing the succession of street or station names at each terminal of the street car tracks, or at any point, at which the car returns over the same track, also 30 to provide means to readily detach and remove the device for indicating streets or stations from its proper location in the front end of the car to the rear end of the car at each reversal of the direction of operation 35 of said car.

I attain these objects by the mechanism illustrated in the accompanying drawings in which—

Figure 1 is a sectional elevation of my device showing the mechanism whereby the successive series of street or station names are brought within view of the passengers on a car.

Fig. 2 is a front view of my device showing the successive series of street or station names traveling in the direction indicated by the arrows shown thereon, also suitable means for indicating the name of the street or station which will be crossed next.

50 Fig. 3 shows the same front view of my device with the mechanism and indicator set for the reverse operation of the names from that shown in Fig. 2.

Fig. 4 shows a cross section of my device 55 on the line 5—5 of Fig. 1 and shows in elevation, the means whereby the street or

station names are successively stepped into the proper position for indicating to passengers the name of the next street or station which will be crossed.

60

Fig. 5 shows an enlarged detail of an endless belt upon which the successive series of names are printed or attached.

Fig. 6 is a section on line 7—7 of Fig. 5 and shows in detail the reinforcement at 65 that part of the endless belt which engages with the stepping mechanism.

Fig. 7 shows an enlarged side elevation of the belt stepping mechanism, and the means whereby said belt is stepped in either direc- 70

Fig. 8 is a section on line 9—9 of Fig. 7 and shows an enlarged detail of that part of the mechanism by which the stepping of the endless belt is reversed.

75

Referring to Fig. 1, 1 represents a casing having a suitable opening indicated at 2—3. Midway of the opening 2—3 a suitably inscribed indicator shutter is supported by means of the pivot pins 5—6 which pass 80 through the hinge members 7—8 attached to the front face 9 of the casing 1. Spring clips 10—11 are suitably attached to the front face of said casing 1 in such position that the indicator shutter 4 may be securely 85 held thereby to the casing 1 over either the opening 2 or the opening 3.

An endless belt 12, is suitably mounted on a series of upper rolls 13, a front terminal roll 14, and a rear terminal roll 15, and a 90 series of lower rolls 16, a front terminal roll 17, and a driving roll 18. The upper rolls 13, 14, and 15 are supported at each end thereof in an adjustable bearing bar 19 which is attached to the casing 1 by means 95 of the adjusting screws 20.

The lower roll 16, 17, and the driving rolls 18 are mounted at each end thereof in bearing bars 21 secured to the casing 1 by bolts 22.

100

Means for successively stepping the driving roll 18 is provided by the mechanism shown in Figs. 4 and 7. The driving roll 18 is provided at one end thereof with an extension shaft 23 which passes through 105 the bearing bar 21 and through the casing 1 and has attached to the end of said shaft 23, a gear wheel 24 which meshes with a stepping gear wheel 25, mounted on a stud 26. The wheel 25 is provided on its outer 110 face with an annular series of stepping pins 27.

Attached to the under side of the casing 1, and in true alinement with the axis of the stud pin 26 and stepping wheel 25, is a bearing block 28 having slidably mounted therein, a square plunger bar 29, which has rotatably attached to the upper end thereof, a socket bearing 30; the lower end 31 of which, extending within a hole 32 in the upper end of the plunger bar 29, is made with a groove 33 into which fits a set screw 34 which is threaded into the plunger bar 29 and holds the socket bearing 30 in position on the plunger bar 29. At the upper side of the socket bearing 30 are formed the bearing lugs 35 through which passes the pivot pin 36, which has mounted thereon the stepping pawl 37 whose sloping lips 38 engage slidably the stepping pins 27.

A double ended spring 39 is attached to the socket bearing 30 by means of the screw 40, the upper end of said spring 39 pressing against the stepping pawl 37 to hold the same in a forward position, and the lower end thereof pressing against one or the other of the flattened faces 41 or 42 of the upper end of the plunger bar 29, thus holding the socket bearing 30 with the stepping pawl 37 in suitable position, with respect to the stepping pins 27, so that said pawl 37 may be set to step the stepping pins in either of two opposite directions, when the plunger bar 29 with the pawl 37 are elevated by the lip 43 of the push rod 44, projecting through the opening 45 in the rail 46 of the street or railroad car.

The upper end of the push rod 44 is held slidably in a bearing 48 attached to the rail 46 by the bolts 49. The lower end of the push rod 44 extends through a hole 50 in the vestibule floor 51 of the street or railroad car, and terminates in a spring block 53, between which and the vestibule floor 51 is mounted a compression spring 54 which tends to hold the push rod 44 in its lower position. The spring block 53 has pivotally attached thereto by means of a pin 55 one end of a lever arm 56, the other end of which projects underneath a hole 57 in the vestibule floor 51 through which is inserted the removable foot plunger 58 by means of which the lever arm 56 is reciprocated upon the pivot bearing 59, secured to the under-side of the vestibule floor 51. A shaft 60 extends from the rear to the front vestibule of the street or railroad car and to this shaft the lever arms 56 are attached, thereby making it possible to operate a similar push rod 44 located similarly at either end of the car from either vestibule.

Means for readily attaching the street or station indicator to the rail 46 of the street or railroad car is provided by the hooks 61 attached to each side of the casing 1 and adapted to engage in brackets 62 attached

to the rail 46 by means of the bolts 63, said indicator being supported upon the shelf 64 attached to the rail 46.

The endless belt 12 is made of suitable flexible material and has printed or attached thereon names 65 of streets or stations and suitable interlining 66, which when stepped into view on the face 9 of the indicator case 1 give the desired indication of an approaching street or station. Reinforcing plates 67 are secured to the edge portions of the endless belt 12, and are made with perforations into which the sprocket teeth 69 engage. A door 70, forming one side of the indicator case 1, provides suitable means for access to the interior mechanism.

In operation, the said indicator is attached in the location provided for same at the front end of the street or railroad car and the proper name of the next intersecting street or station which will be crossed by the car will be set at the proper position for the next street or station, by placing the foot on the foot plunger 58, and stepping the endless belt into the proper position either up or down on the face 9 of the indicator case 1, the socket bearing 30 having been previously turned to bring the stepping pawl 37 into the proper position for turning the stepping pins in the desired direction, and the indicator shutter 4 having been placed in proper up or down position.

After the street or railroad car has passed the first intersecting street or station, the conductor of the street or railroad car, steps upon the foot plunger 58, which operation steps the name of the first intersecting street or station out of view and places the next street or station name into the indicated position. This operation is then similarly repeated for each street or station to the end of the line, when the indicator and foot plunger will be removed to the opposite end of the car, and the stepping mechanism and the indicator shutter reversed. The device is then ready for operation in the reverse direction.

It is obvious that a similar indicator may be permanently attached at either or both ends of the car and be simultaneously operated from either vestibule of the car.

Having thus described my invention what I claim, and desire to secure by Letters Patent, is—

1. In a street or station indicator, the combination with a casing, an indicator apron, and rolls for supporting said apron, of a wheel connected with one of said rolls, an annular series of pins on said wheel, a vertically movable bar, a member swiveled to said bar, a pawl pivoted to said swiveled member and adapted to coöperate with the annular series of pins to propel the wheel carrying said pins, a double-ended spring secured to said swiveled member and en-

gaging the pawl and the bar, whereby the pawl will be retained in operative relation to the wheel to drive the same in one direction or the other when the bar is raised, and 5 means for raising said bar.

2. In a street or station indicator, the combination with a casing having an opening in its front, and an endless indicator apron movable past said opening, of rolls for supporting and guiding said apron, one of said rolls provided with means coöperable with the apron to move the latter, a pinion carried by said last-mentioned roll, a gear meshing with said pinion, an annular series 10 of pins carried by said gear, a vertically movable bar, a single pawl adjustably mounted on said bar, said pawl adapted to enter between the pins on said gear and having a cam face to engage one of said pins to propel said gear, and means for moving said bar vertically for actuating the pawl to turn said gear in one direction or the other for actuating the apron in one direction or the other.
- 25 3. In a street or station indicator, the combination with a casing having an opening in

its front, an endless indicator apron movable past said opening, supporting rolls for the apron, and a driving roll, of a pinion on the driving roll, a gear meshing with said pinion, an annular series of pins on said gear, a vertically movable bar, a pawl, a swivel mounting for said pawl attached to the upper end of said bar, said pawl co-operable with the annular series of pins to 30 move the gear and the apron in one direction or the other, and a spring device attached to said swivel mounting and engaging said bar to normally prevent swiveling of the pawl, for holding said swiveled pawl 35 in one or another position of adjustment to control the direction of movement of said gear and apron, and means for moving said pawl-carrying bar vertically.

In testimony whereof, I have hereunto 40 set my hand in the presence of two subscribing witnesses.

CHARLES W. MOORE.
